UNITED STATES PATENT OFFICE.

HARVEY A. MAILLOUX, OF HAVERHILL, MASSACHUSETTS.

TIME-CONTROLLED FURNACE-REGULATOR.

1,317,172.

Specification of Letters Patent. Patented Sept. 30, 1919.

Application filed January 11, 1919. Serial No. 270,708.

To all whom it may concern:

Be it known that I, HARVEY A. MAILLOUX, a citizen of the United States, residing at Haverhill, in the county of Essex and State 5 of Massachusetts, have invented certain new and useful Improvements in Time-Controlled Furnace-Regulators, of which the following is a specification, reference being had to the accompanying drawings.

10 This invention relates to means for operating the drafts and check dampers of stoves, furnaces and like heating constructions, and particularly to a time-operated device of this character.

15 The general object of this invention is to provide a very simple mechanism for the purpose of automatically closing the check damper or door of a furnace and automatically opening the draft door of the furnace 20 by means of a clock.

25 A further object is to provide a device of this character which may be easily applied to all furnaces having checks and draft doors, and which is extremely simple in construction and easy of operation.

Other objects will appear in the course of the following description.

My invention is illustrated in the accompanying drawings, wherein:—

30 Figure 1 is an elevation of a furnace showing my improved draft regulating mechanism applied thereto and partly broken away; and

Fig. 2 is a front elevation of the draft controlling mechanism showing the trigger unlatched, the parts being broken away.

Referring to these drawings, 10 designates a furnace such as is used for heating houses and provided with a draft door 11 and 40 mounted upon the furnace or heater is a pivoted arm 12 connected by a chain 13 to the draft door and operatively connected to a draft check or damper 14. These parts are of any ordinary or suitable construction, it 45 being understood, of course, that the arm 12 carries a weight 15 which acts to lift the draft door 11 and close the check damper 14.

50 Mounted upon a shelf or other support 16 which may be suspended from the ceiling is a brace 17 which may be disposed between the shelf 16 and the pivoted arm 12, so as to support the latter against the action of the weight 15, in which position the door 11 will be closed and the check 14 will be 55 opened. Attached to the extremity of the brace 17 is a cord 18 which extends over a

pulley or through an eye 19 and to the end of which is attached a weight 20. This weight rests upon a suspended shelf 21 which is pivoted at 22 and which is held 60 in a raised or weight supporting position by a trigger or latch 23 pivoted in any suitable manner, as upon a depending rod 24. This depending rod supports a shelf 25 having thereon an alarm clock 26 of any usual 65 or suitable character and illustrated as provided with the alarm sounding clapper 27. This clapper is connected by a cord 28 to the trigger 23.

At night, when it is desired that the check 70 shall be opened and the door 11 closed the arm 12 is raised and the brace 17 is disposed between the arm and the shelf 16 or other support for the brace. The pivoted shelf 21 is raised and latched by the trigger 23 75 and the weight 20 is rested on this shelf. The clock, of course, is set so as to sound an alarm at any desired time, as for instance at seven o'clock in the morning, and when the alarm goes off the vibrations of the clapper 27 will, through the cord 28, withdraw the trigger from its engagement with the shelf whereupon the weight 20 will fall pulling on the cord 18 and pulling the brace out from beneath the arm 12 whereupon the 85 arm 12 will drop under the weight 15 and open the draft 11 while closing the check damper.

It is obvious that by this means, heat can be checked at night when the heat is not 90 needed and released at any time desired in the morning without the necessity of any one manually opening the draft and closing the check. It will further be seen that the device can be manufactured and sold at a 95 small price and that it may be readily installed. It will be seen that the device may be removed at any time and that it may be readily applied to any form of heater as it is not part of the heater itself. There are 100 no springs, or other mechanism to get out of order.

I claim:—

1. The combination with a heater having a draft door, a check, and a pivoted arm connected at one end to the draft door and at the other end to the check, the arm being provided with a weight tending to close the check and open the draft door, of a releasable brace adapted to be disposed beneath 110 the arm to hold it supported, a weight connected to said brace to pull it from beneath

- said arm, a pivoted shelf upon which said weight normally rests and holding it from downward movement, a trigger engaging the shelf, and a clock having its alarm mechanism operatively connected to the trigger to release it at a predetermined time to thereby release the shelf and permit the downward movement of the weight and the release of said brace.
- 19 2. A mechanism of the character described and for the purpose stated comprising a shelf adapted to be disposed beneath the weighted end of a draft controlling arm, a brace adapted to be disposed between the draft controlling arms of the shelf, a frame having an eye, a flexible connection extend-

ing from the brace through said eye and connected to a weight, a shelf pivoted to the frame and adapted to support a weight, a trigger pivoted on the frame and adapted in one position to engage the shelf to prevent its downward movement under the weight, and an alarm clock having a flexible connection from the trigger to its alarm mechanism.

25
In testimony whereof I hereunto affix my signature in the presence of two witnesses.

HARVEY A. MAILLOUX.
